UNITED STATES PATENT OFFICE.

CHARLOTTE E. PAGE, OF CHICAGO, ILLINOIS.

DESIGN FOR A KNOT FOR SCARF, &c.

SPECIFICATION forming part of Design No. 16,417, dated December 15, 1885.

Application filed September 22, 1885. Serial No. 177,872. Term of patent 14 years.

To all whom it may concern:

Be it known that I, CHARLOTTE E. PAGE, a citizen of the United States, residing at Chicago, in the county of Cook and State of Illinois, have invented and produced a new and original Design for a Knot for Wearing Apparel, of which the following is a specification, to wit:

My invention relates to designs for the garniture knots of wearing-apparel, such as are worn upon neckties, dress-fronts, &c.; and the same consists of the knot hereinafter described, and shown in the figures of drawings herewith furnished.

15 The leading feature of my design consists of a knot having a base, body, and apex. The base is of irregular oval outline. The body consists of a series of irregular puffed ridges or elevations, *a*, which extend inward 20 from the outline of the base to the center of the knot, where the material is raised to form a blunted or rounded apex. Between the puffed ridges are irregular depressions or 25 grooves *b*, which conform in general to the elevated or puffed ridges *a*. Both the ridges and the depressions converge toward the center of the knot and disappear within the apex.

The accompanying drawings represent my knot design as applied to a necktie.

In Figure 1 the whole of the necktie is 30 shown in dotted outline, while the knot is situated in the central upper portion of the face, and is delineated in full lines. Fig. 2 represents a side view of the knot.

I claim—

35 The design for the garniture knot herein described and shown, the same consisting of a base, body, and apex, the base being of irregular oval outline, the body having a series of irregular elevations or ridges arising from 40 the outline of the base, and terminating in the blunted or rounded apex, and having between the said elevations and conforming thereto a series of irregular depressions or grooves, the said elevations and depressions 45 converging and disappearing together within the central portion of the apex, as shown.

In testimony whereof I affix my signature in presence of two witnesses.

CHARLOTTE E. PAGE.

Witnesses:

W. C. McARTHUR,
H. HARRISON.
